UNITED STATES PATENT OFFICE.

ELLIS S. LINCOLN AND ERNST LARSSON, OF MANSFIELD, OHIO, ASSIGNORS TO THE OHIO BRASS COMPANY, OF MANSFIELD, OHIO, A CORPORATION OF NEW JERSEY.

TROLLEY BASE.

Application filed March 25, 1922. Serial No. 546,606.

To all whom it may concern:

Be it known that we, ELLIS S. LINCOLN, a citizen of Sweden, and ERNST LARSSON, a citizen of the United States of America, 5 residing at Mansfield, in the county of Richland and State of Ohio, have invented certain new and useful Improvements in Trolley Bases, of which the following is a specification.

10 Our invention relates to a trolley base for use on vehicles employing a trolley pole to the upper end of which is attached a current collector to engage with an overhead trolley conductor.

15 The object of our invention is to produce a mechanism which will permit of free rotation of the pole supporting portion about a vertical axis and to maintain tension upon the pole supporting member in order to urge 20 the pole in an upward direction and so that the trolley collector at the upper end of the pole will bear against the trolley wire with reasonably uniform tension throughout a practical working range as measured by the 25 ordinary variation in the height of the trolley wire. Other objects will appear from the description of the construction and out of the invention hereinafter more fully set forth.

30 The invention resides in the construction, combination and relation of the various parts hereinafter described and shown in the drawing.

In the drawings accompanying this specification—

35 Fig. 1 shows a side view of my invention in elevation held in a locked position against operation.

Fig. 2 shows a top plan view of Fig. 1.

40 Fig. 3 shows a front or end view of Fig. 2 in partial section.

Fig. 4 shows a side view of my invention in elevation in operative position.

Fig. 5 is a cross sectional view on the line 45 5—5 of Fig. 4.

Fig. 6 is a view in partial section on the line 6—6 of Fig. 2.

In the preferred form of our invention

we employ a base having a broad platform 1 which is mounted on the roof of the vehicle by means of bolts passing through the recesses 2 and mounted on the platform 1 is a pedestal 3 upon which the moving parts of the invention are mounted.

The moving parts of our invention comprise an inverted cup shaped member 4 which is placed over the pedestal 3. Interposed between the members 3 and 4 is a series of roller bearings 5 mounted in a cage forming a unit as is usually the manner and the common way in which roller bearings are mounted. Projecting from the member 4 are two lugs 6—6 provided with alined recesses through which pass a pin 7 and held in place by means of a spring 65 cotter 8—8. Also mounted on the member 4 are two lugs 9—9 provided with alined recesses through which pass a pin 10, the pin being held in place by means of the spring cotter 11—11. Pivotally mounted on a projecting stud 12 secured to the member 4, is a movable latch 13 held in place by the spring cotter 14. Pivotally mounted on the pin 10 is a yoke shaped or forked arm 15 provided with an elongated member 16 which divides into the arms 17—17 and which arms are provided with alined recesses for mounting upon the pin 10.

Each of the fork members 17 are provided with extension members 18—18 one of which 80 is adapted to be engaged by the pivotally mounted latch 13 whereby the forked arm 15, together with the trolley pole, may be held in a lowered or inoperative position as shown in Fig. 1. At the outer end of the 85 arm 15 and intermediate its ends are clamping members 19—19 held in place by means of the studs and nuts 20—20. The members 19 are provided with a semi-circular groove 21 which has a counter part groove 22 in the member 16 all to receive the lower end of the trolley pole 23 which is clamped in position by means of the studs and nuts 20—20. At the outer end of the forked 90 arm 15 is provided a slidble member 24 95 having a stud 25 secured thereto which

passes through a recess in the lug 26 which is secured to the outer end of the member 16. The nut 27 portably engaging the stud 25 permits adjustment of the slideable member longitudinal of the arm 16. The slideable member 24 is provided with inwardly projecting flanges 28-28 which engage with the flanges 29-29 on the member 16 thereby retaining the member 24 in position 10 on the arm 16, but permitting it to move longitudinal thereof and which movement is controlled by the nut 27 on the stud 25.

Interposed between the pin 7 and the movable member 24 is a plurality of springs 30 15 normally under tension tending to constantly urge the member 15 to pivot upwardly about the pin 10. Each spring is attached to the movable member 24 by means of the eye 31 engaging the hook member 32 and to the pin 7 by means of the eye 33 engaging therewith. The tension in the spring can be adjusted by means of the nut 27 operating on the stud 25.

Projecting on the member 4 in the same 25 direction as the arm 15 and below the same are two studs 34-34 each provided with a spring 35 and having interposed between one end of the spring and the member 4 a movable plate 36 provided with recesses 30 through which the studs 34 pass. The springs are held in position upon the studs 34-34 by means of the nuts 37-37 and which in turn are prevented from rotating 35 after being properly positioned to tension the springs 35-35, by means of the pins 38-38.

The function of the parts 34 to 38, inclusive is to act as a buffer in case the trolley collector at the upper end of the pole 23 40 should leave the wire, as in that case the pole would be rapidly raised under tension of the springs 30, but after rising to a predetermined height the lugs 18-18 would engage with the plate 36 and be arrested in 45 its upward rise and a cushioning effect would be afforded by the springs 35-35. The arrangement of the parts as shown and especially having the springs 30, fork member 15 and buffering springs 35 arranged in the 50 same longitudinal direction and directly above and below each other gives a very compact arrangement which is especially adapted to the mounting of two bases side by side upon a vehicle intended to operate 55 by means of two overhead conductors as is the case with trackless trolley operation, as the arrangement shown permits the bases to swivel about their vertical axes without interfering with each other as the lateral 60 space taken up by the moving parts can be made very limited.

By positioning the fulcrum points 7 and 10 as shown, namely, the one above the other and out of the same vertical plane and with 65 the proper relative spacing, we are able to

secure practically a uniform tension of the current collecting device at the end of the pole 23 against the trolley wire within practical working limits of movement of the trolley pole 23.

Having disclosed our invention, we claim:-

1. A trolley base comprising a base member for attachment to a vehicle and provided with a pedestal, a turret rotatably mounted on the pedestal and provided with anti-friction members therebetween, an arm pivotally mounted on the turret to receive a trolley pole and pivot in a vertical plane, means on the arm to engage and clamp the trolley pole to the arm, means on the turret to receive spring means, adjustable means on the arm to receive spring means, spring means interposed between the last two means operating to force the arm upward about 85 its pivotal point on the turret, pivotal stop means on the turret to be moved at will, stop means on the arm to be engaged by the stop means on the turret to hold the arm in a lowered or inoperative position and resilient stop means secured to the turret to be engaged by the stop means on the arm to yieldingly arrest the upward movement of the arm beyond a predetermined point, the spring means, arm and resilient stop means 95 all extending in the same direction from the vertical axis of the turret.

2. A trolley base comprising a base member for attachment to a vehicle and provided with a pedestal, a turret rotatably 100 mounted on the pedestal and provided with anti-friction members therebetween, an arm pivotally mounted on the turret to receive a trolley pole and pivot in a vertical plane, means on the arm to engage and clamp the trolley pole to the arm, means on the turret to receive spring means, adjustable means on the arm to receive spring means, spring means interposed between the last two means 105 operating to force the arm upward about its pivotal point on the turret, pivotal stop means on the turret to be moved at will, stop means on the arm to be engaged by the stop means on the turret to hold the arm in a lowered or inoperative position and resilient stop means secured to the turret to be engaged by the stop means on the arm to yieldingly arrest the upward movement 110 of the arm beyond a predetermined point.

3. A trolley base comprising a base member for attachment to a vehicle and provided with a pedestal, a turret rotatably mounted on the pedestal and provided with anti-friction members therebetween, an arm pivotally mounted on the turret to receive a trolley pole and pivot in a vertical plane, means on the arm to engage and clamp the trolley pole to the arm, means on the turret to receive spring means, adjustable means on the arm to receive spring means, spring 125 130

- means interposed between the last two means operating to force the arm upward about its pivotal point on the turret, pivotal stop means on the turret to be moved at will, 5 stop means on the arm to be engaged by the stop means on the turret to hold the arm in a lowered or inoperative position, the spring means and arm all extending in the same direction from the vertical axis of the 10 turret.
4. A trolley base comprising a base member for attachment to a vehicle and provided with a pedestal, a turret rotatably mounted on the pedestal and provided with anti-friction members therebetween, an arm pivotally mounted on the turret to receive a trolley pole and pivot in a vertical plane, means on the arm to engage and clamp the trolley pole to the arm, means on the turret to be moved at will, 15 to receive spring means, adjustable means operating to force the arm upward about its pivotal point on the turret, pivotal stop means on the turret to hold the arm in a lowered or inoperative position.
5. A trolley base comprising a base member for attachment to a vehicle and provided with a pedestal, a turret rotatably mounted on the pedestal and provided with anti-friction members therebetween, an arm pivotally mounted on the turret to receive a trolley 20 pole and pivot in a vertical plane, means on the arm to engage and clamp the trolley pole to the arm, means on the arm to receive spring means, spring means interposed between the last two means operating to force the arm upward about its pivotal point on the turret, pivotal stop means on the turret to be moved at will, 25 means on the arm to be engaged by the stop means on the turret to hold the arm in a lowered or inoperative position.
6. A trolley base comprising a base member for attachment to a vehicle and provided with a pedestal, a turret rotatably mounted on the pedestal and provided with anti-friction members therebetween, an arm pivotally mounted on the turret to receive a trolley 30 pole and pivot in a vertical plane, means on the arm to engage and clamp the trolley pole to the arm, means on the arm to receive spring means, spring means interposed between the last two means operating to force the arm upward about its pivotal point on the turret, stop means on the arm and resilient stop means secured to the 35 turret to be engaged by the stop means on the arm to yieldingly arrest the upward movement of the arm beyond a predetermined point, the spring means and arm and resilient stop means all extending in the same direction from the vertical axis of the 40 turret.
7. A trolley base comprising in combination a base member to be secured to a vehicle and provided with a pedestal, a rotatable turret mounted on the pedestal, an arm pivotally mounted on the turret to swing in a vertical plane, a 45 spring interposed between the turret and arm, means on the turret to receive one end of the spring, adjustable means slidably mounted on the arm to receive the other end of the spring, means on the arm to maintain the adjustable means thereon, means on the adjustable means cooperating with means on the arm to control the movement of the adjustable members and vary the tension of the 50 spring.
8. A trolley base comprising a base member provided with a pedestal, a turret mounted thereon to rotate about the vertical axis of the pedestal, an arm pivoted at one end to the turret to operate in a vertical plane, a spring secured to the turret and to adjustable means on the arm, the adjustable means comprising a slidable member provided with inwardly projecting flanges co-operating with outwardly projecting flanges 55 on the arm to retain the adjustable member on the arm and means on the adjustable member cooperating with means on the arm to move the adjustable member thereon and vary the tension of the spring.
9. A trolley base comprising in combination a base member to be secured to a vehicle and provided with a pedestal, a rotatable turret mounted on the pedestal, an arm pivotally mounted on the turret to receive a trolley pole, spring means secured to the turret at a point in a plane above the pivotal mounting of the arm operating to rotate the arm upwardly about its pivotal point, and means to yieldingly arrest the upward movement of the arm at a predetermined point comprising a resilient means positioned below the arm and secured to the turret, a member arranged to engage the resilient means in movable relation therewith and means on the arm to engage the member when the arm has moved about its pivotal point a predetermined amount.
10. A trolley base provided with a base member for attachment to a vehicle, a rotatable member mounted thereon and a spring operated arm pivoted to the rotatable member to move in a vertical plane and having in combination therewith means to arrest the movement of the arm in one direction comprising a plurality of studs projecting from the rotatable member, a spring mounted on each stud, a member slidably mounted on the studs and engaging the 60 springs, means on the stud to retain the 65 resilient stop means secured to the tur- 70 75 80 85 90 95 100 105 110 115 120 125 130

springs in place and adjust the tension thereof and means on the arm to engage the slidably mounted member on the studs.

11. A trolley base comprising in combination a base member, a turret rotatably mounted thereon, an arm pivotally mounted on the turret to move vertically, a spring operating to move the arm about its pivotal point, stop means on the turret to be moved

at will to hold the arm against movement, 10 resilient means on the turret to arrest movement of the arm and common means on the arm to engage the stop means and the resilient means for the purpose described.

In testimony whereof we affix our signatures.

ELLIS S. LINCOLN.
ERNST LARSSON.
